UNITED STATES PATENT OFFICE.

AUGUST BAUM, OF CHICAGO, ILLINOIS.

POCKET.

Application filed December 10, 1927. Serial No. 239,030.

The invention relates to safety pockets and its principal object consists in providing a pocket in a garment which will effectively prevent the surreptitious removal of the contents.

5 It is a further object of the invention to provide a pocket in trousers which is constructed to co-operate with the belt to prevent a hand from reaching inside of the 10 pocket.

It is a further object of the invention to provide reinforced means to prevent the cutting of the pocket and the removal of its 15 contents.

20 A still further object of the invention is to provide a pocket wall with a narrow auxiliary pocket which receives a longitudinal member secured to a pocketbook so as to prevent the pulling out of the pocketbook after 25 the bottom of the pocket has been cut or otherwise opened.

With these and other objects in view, which will appear from the description of the invention, the latter comprises the means 25 described in the following specification particularly pointed out in the claims forming a part thereof and illustrated in the accompanying drawing in which:

30 Figure 1 is a fragmentary perspective view of the rear part of trousers in which the improved safety pocket is incorporated.

Figure 2 is a section on the line 2—2 of Figure 1.

35 Figure 3 is a fragmentary inside view of the trousers with parts broken away to disclose interior construction of the pocket.

Figure 4 is a section of the line 4—4 of Figure 3.

40 Figure 5 is a perspective view of a pocketbook used in connection with the improved pocket.

45 Referring to the several views of the drawing, 10 generally indicates the trousers which are provided with a slit 11, to afford access to a pocket comprising the walls 12 and 13 which on three sides are sewed together by a seam 14 but remaining open on top. The wall 13 is secured by a seam 15 to the trouser wall 10^a, and the wall 12, is also secured to 50 the trouser wall 10^b, which is separated from the trouser wall 10^a by a slit 11, as will be readily understood by reference to Figure 2. The trouser wall 10^a, where the slit 11 is located is provided with a hem 16, through 55 which the seam 15 extends and to the inner

lower end of the hem 16 is secured an extension 17, which is located centrally with respect to the pocket and extends upwardly therefrom to a height sufficient to overlap a belt 18 used in connection with the trousers. 60 The extension 17 comprises double walls 19 and 20 in order to house upright reinforcing members or stays 21 and the extension 17 is folded upon itself and the free end is secured to an intermediate portion of the extension by 65 a seam 21 forming thereby a loop 22 for the passage of the belt 18. The rear portion of the loop 22 is provided with a vertical slit 23 for the passage of a button 24 secured to the trouser wall 10^b so that even in the absence of a belt the extension 17 is held close to the trouser wall and its separation therefrom is prevented by the button 24 which is hidden from view. The pocket wall 13 is equipped with a centrally located narrow 70 pocket 25 which by a seam 26 is closed on three sides but open at the top.

75 A pocketbook 27, of any desired construction, is provided with a blade 28, secured at the top to the pocketbook as at 29 but having 80 its end 30, free and spaced from the body of the pocketbook. In use the pocketbook is inserted so that the blade 28 is received in the pocket 25, as is shown in Figure 2. Thereupon the belt is threaded through the loop 22 of the extension 17 and the extension is secured to the trouser wall 10^b by the button 24 being forced through the slit 23. If an attempt is made to force a hand into the pocket the extension 17 will prevent such 85 attempt as it is held close to the trouser wall by the belt and by the button 24. Again, if an attempt is made to cut through the extension such cutting will not be effective 90 because the reinforcement or stays will prevent it from being cut off. Again, if the bottom of the pocket is cut off the pocketbook with its content cannot be withdrawn because the inner pocket 25 will engage with the riveted end of the blade 28 and thus prevent 95 withdrawal of the pocketbook. 100

From the foregoing follows that the safety pocket adequately protects its content from withdrawal either upwardly or downwardly so that it is practically impossible to remove 105 the content of the pocket surreptitiously.

While the drawing shows a preferred embodiment of the invention numerous changes and alterations can be made without departing from the spirit of the invention. It 110

is, therefore, not my intention of confining myself to the exact details of construction and arrangement of parts as shown, but wish to include all changes, alterations, variations, and modifications, constituting departures within the scope of the invention as defined in the appended claims.

I claim:

1. A safety-pocket for trousers having a belt, including reinforced means forming an extension of the outer pocket wall for rendering access to said pocket difficult, said reinforced means being formed to permit said belt to be threaded therethrough.

2. A safety-pocket for trousers having a belt, including reinforced means forming an extension of the outer pocket wall for rendering access to said pocket difficult, said reinforced means being formed to permit said belt to be threaded therethrough, and means for releasably securing said extension to the trousers.

In witness whereof I affix my signature.

AUGUST BAUM.
